DESIGN FOR A BUCKLE SLIDE

Seymour J. Lesnik, Newark, N. J., assignor to
American Record Corporation, New York, N. Y.,
a corporation of New York

Application March 7, 1935, Serial No. 55,772

Term of patent 3½ years

To all whom it may concern:

Be it known that I, Seymour J. Lesnik, a citizen of the United States, residing at 198 Hansbury Avenue, in the city of Newark, in the county of Essex and State of New Jersey, have invented a new, original, and ornamental Design for Buckle Slides, of which the following is a specification, reference being had to the accompanying drawing, forming part thereof.

Figure 1 is a plan view of a buckle slide, showing my new design.

Figure 2 is a side elevational view of the buckle slide.

I claim:

The ornamental design for a buckle slide, as shown.

SEYMOUR J. LESNIK.
